DRIVING MECHANISM

Paul K. Beemer, Inglewood, and Henry O. Fuchs, Los Angeles, Calif., assignors to Preco Incorporated, Los Angeles, Calif., a corporation of California

Application May 7, 1946, Serial No. 667,803

14 Claims. (Cl. 105—114)

1

This invention refers to improvements in driving mechanisms for accessories in transport vehicles and, in certain features embodies improvements upon the driving mechanism shown in Patent No. 2,349,315, William E. Van Dorn, issued May 23, 1944, and which driving mechanism is the subject-matter of a divisional application, Ser. 498,536, filed August 13, 1943, as a division of the application which eventuated in said patent. Said application has now issued as Patent 2,413,158 on December 24, 1946. The present improved driving mechanism is generally applicable to the driving of various types of accessories from the running gear of a vehicle. It has been designed particularly with a view to the driving of an air impeller for railroad car ventilation and for air circulation in refrigerator cars, and will be so described in the following detailed specification but without limitation thereto.

The general purposes of the present invention are to provide a simplified form of the type of mechanism above referred to. In that type of mechanism a drive shaft is hung upon the body of the car in such manner that a traction roller or equivalent drive transmitting means at one end of the drive shaft may move freely to follow and accommodate the relative movements between the car body and the running gear; while the other end of the drive shaft is so mounted that a drive transmission to the accessory driving shaft is kept in effective drive transmitting condition.

The present invention, among other things, has to do with improvements in the manner and structure of support for that driving shaft. Other features of improvement will be set out in the course of the following detailed description of present preferred embodiments of the invention, reference for the purpose being had to the accompanying drawings in which:

Fig. 1 is a fragmentary section transverse of the car body showing the driving mechanism applied to the driving of a typical air impeller; the section being taken as indicated by line 1—1 on Fig. 2;

Fig. 2 is a sectional end elevation of the mechanism shown in Fig. 1, the section being taken on line 2—2 of Fig. 1;

Fig. 3 is an enlarged detail section taken as indicated by line 3—3 on Fig. 1;

Fig. 4 is an enlarged detail section taken on line 4—4 of Fig. 1;

Fig. 5 is an enlarged detail section taken on line 5—5 of Fig. 1;

2

Fig. 5a is a section similar to that of Fig. 5 and showing a modified form;

Fig. 6 is a detail section on line 6—6 of Fig. 5;

Fig. 7 is a longitudinal section showing the drive shaft and its immediate appurtenances, and taken as indicated by line 7—7 on Fig. 5;

Fig. 8 is a fragmentary section, similar to portions of the section of Fig. 7, showing a modified form of traction roller;

10. Fig. 9 is an enlarged detail section taken as indicated by line 9—9 on Fig. 2;

Fig. 10 is a detail section on line 10—10 of Fig. 7;

Fig. 11 is a view similar in aspect to Fig. 1 and showing a modification in the driving mechanism; and

Fig. 12 is an enlarged detail section showing the modified traction roller shown in Fig. 11.

In the drawings, parts of a typical car body structure are shown, including floor structure 10 and side wall structure 11. A typical air impeller unit, such as that set out in the Van Dorn patent above referred to is shown at 12, and its driving shaft is shown at 13. For the purposes of our invention the driving shaft 13 is not necessarily the shaft which directly drives air impeller 12; it may be any shaft through which the accessory is driven. In this particular illustration, however, the air impeller is mounted on the car floor with its shaft extending transversely of the car; and it is most convenient and simple to extend that shaft 13 outwardly through or into the side wall structure 11 and to apply the drive transmission from the driving shaft of the drive mechanism directly to that extended drive shaft 13. Accordingly, as here shown, the accessory driving shaft 13 extends out through the inner facing 11a of the car wall into and through a recess 11b which is formed in the car wall. In that recess shaft 13 is equipped with a driving sheave 14; and at its end the shaft 13 is equipped with an auxiliary drive adapter 15 which lies in an opening 16 in the exterior wall sheathing 11c and substantially flush with the outer surface of that sheathing.

Under the car floor a hollow mounting shaft 20 is hung from the car body in a position substantially horizontal and transverse of the length of the car. At its inner end shaft 20 may be rotatably supported in a simple bearing bracket 21 which is mounted upon a part of the longitudinal structural beam 22 which forms a part of the car body structure. At its outer end shaft 20 is mounted to rotate on the reduced end 23 of a plug shaped fitting 24 which is mounted in

a supporting plate 25. (See Fig. 9 for the details of this mounting.) Plug 24 is rotatably adjustable in plate 25 and is secured to the plate and set in any adjusted position by the studs or bolts 26 shown in Fig. 2. The inner end of plug 24 is slotted at 27 to receive one end of a torsion spring 28 which lies within hollow shaft 20 and whose other end (see Figs. 1 and 4) is held in a slotted plug 29 fixed in shaft 20 in any suitable manner as by a bolt or rivet 30. By proper adjustment and setting of plug 24, which is equipped with wrench sockets 31 for the purpose, flat spring 28 is put under an initial torsional strain which tends to rotate shaft 20 and the parts attached thereto in the direction indicated by the arrows in the several views, counter-clockwise as viewed in the aspects of Figs. 2, 3 and 5. The plug may then be secured in its set position by the bolts 26. To accommodate the rotational adjustment of the plug either it or plate 25 may be provided with slotted openings or a series of bolt holes. These are not shown in the drawings, the illustration being based on the supposition that bolt holes are drilled through plate 25 in the positions which suit the adjusted position of the plug.

The torsion spring 28 is specifically shown in the drawings in the form of a flat bar with its ends connected with plug 24 and shaft 20 by the simple expedient of being confined in slots. That is a preferred form of the spring arrangement. But the spring bar may be of other cross-sectional shapes, may be composed of two or more bars which together form a laminated bar, and may be attached at its ends in other manners.

The driving shaft 40 (see particularly Fig. 7) is mounted in bearings in a tubular shaft carrier 41. As here illustrated, the preferred arrangement for mounting shaft 40 in the carrier 41 is as follows. The shaft is directly carried by two ball bearings 42, the outer races of which are snugly fitted into annular adapters 43 which have inwardly turned annular flanges 44 at their inner ends and outwardly turned annular flanges 45 at their outer ends. A fairly soft annular rubber bushing 46 fits directly into each end of tubular carrier 41, the bushing having an outwardly turned flange 47 at its outer end resting against the end of tubular carrier 41. One of the cylindric faces of rubber bushing 46 is corrugated or toothed, preferably the inner surface as shown at 48 in Fig. 10.

The described structure is highly advantageous for inexpensive and quick assembly of the parts. The metal adapter 43, which may be made of pressed sheet metal, fits the outer race of the ball bearing tightly and gives the bearing a good annular seat on the rubber bushing 46. With the metal bushing 43 inserted into rubber bushing 46, the whole assembly including the bearing, and the metal and rubber bushings, is then easily force-fitted into tube 41, the toothed formation at 48 allowing an easy compressibility of the rubber bushing. And with the rubber bushing so constructed, the ball bearings, although securely held in place in tube 41, are allowed sufficient easy freedom for axial alignment with each other although the ends of tube 41 may not have been either machined at all or machined to any great accuracy.

Driving shaft 40 is driven at its inner end (its end closer to the car center) from the running gear of the car; from some element which rotates with the wheel and axle unit, and prefer-

ably directly from a car wheel, such as the car wheel illustrated at 50. Driving from the car wheel, the drive is preferably through a traction roller 49 which normally engages the tread of the wheel.

Fig. 7 shows one preferred form of such a traction roller and Fig. 8 a modified form. In Fig. 7 a flanged hub 51 is mounted on the inner end of shaft 40 and the members which make up the body of the traction roller are bolted to the flange of hub 51. The main body of the roller includes a pressed sheet metal member 52 having an inwardly extending flange 53 which is bolted against the flange of hub 51. The body 52 has a substantially cylindric portion 54 and a frusto-conical portion 55 at that end of cylindric portion 54 which faces inwardly in a direction away from the inner end of driving shaft 40. The pressed sheet metal body is covered with a tread of suitable material, for instance, vulcanized rubber. The traction tire indicated generally by the numeral 56 has a generally cylindric tread portion 57 and a frusto-conical tread portion 58.

In the form of traction roller shown in Fig. 7 the frusto-conical portion 58 is extended by the conical surface 59 of a metal cone 60, the taper of the cone being substantially the same as the taper of the conical tread surface 58. Bolts 61 serve to bolt both the cone 60 and the flange 53 of the main roller body to the flanged hub 51.

Immediately inward of the traction roller a fixed guard member 65 is fixedly mounted on tube 41. This guard member may be most conveniently formed by a piece of strap steel bent to the U-conformation shown in Fig. 5 and welded at its ends at 66 to tube 41. The guard lies close to the larger or outer end of the traction roller, and its rounded part which projects furthest from the axis of shaft 40 lies somewhat radially inwardly of the outer cylindric tread surface 57 of the traction roller. The approximate relationship is shown in Figs. 5 and 7. The functions of this guard member, and the modified form 65a shown in Fig. 11, will be explained later when the action of the roller on the car wheel is explained.

Shaft carrier tube 41 and shaft 40 are supported on mounting shaft 20 in such a manner that 40 and 41 are movable as a whole in a generally vertical direction, specifically in this particular structure about the transversely extending axis of mounting shaft 20, and also in such a manner that each end of drive shaft 40 is allowed similar movement independently. The mounting 55 shown in Figs. 1 to 6 comprises a single radial arm 70 rigidly mounted on mounting shaft 20 and carrying tube 41 so that it and drive shaft 40 have a swivelling movement about the axis of arm 70. In a preferred form such as shown in Fig. 5 arm 60 70 is made up of an external tube 71 attached to mounting shaft 20 by welding as shown at 72. Within tube 71 a smaller tube 72 fits movably, and a cross pin 73 set in outer tube 71 passes through slots 74 in the wall of tube 72 to prevent relative 65 longitudinal movement of the tube but to allow a sufficient amount of relative rotation. The outer end of inner tube 72 has the carrier tube 41 rigidly mounted on it, as by welding as at 75.

Tube 41 and driving shaft 40 are supported in 70 such a position that the tread face 57 of the traction roller is normally in about the central plane of the car wheel tread as shown in Fig. 1, and a belt sheave 80 on the other or outer end of drive shaft 40 is in the plane of sheave 14 on accessory 75 driving shaft 13. A driving belt 81 encircles the

two sheaves. The torsional strain of torsion spring 28, tending to rotate the parts in the relative directions indicated, tends at all times to press the traction roller against the car wheel tread and also to move sheave 80 downwardly away from sheave 14 and to keep driving belt 81 tight. With any given setting of spring 28 the relation of the forces which press the traction roller against the car wheel and which tense the driving belt depends upon the location of swivel arm 70; that is, upon the relative spacings of that arm from the traction roller and from sheave 80. In the relative position of the arm shown in Fig. 1 the force applied to the traction roller is the greater, but that relative position may be varied as is found desirable.

The relative movement between the car body and car wheel includes relative vertical movement of the spring-supported body, and relative swiveling movements of the car wheel about the swiveling axis of the truck. In following the car wheel during both such relative movements the traction roller moves up and down in a line of movement which is generally about the axis of mounting shaft 20, while sheave 80 and the outer end of driving shaft 40 remain substantially stationary. In operation, the only vertical movement of sheave 80 and its end of the shaft is the slight movement which takes place under the pressure of spring 28 to keep belt 81 tight as it stretches or shrinks. Thus, in practical operation driving shaft 40 swings up and down in a plane around mounting shaft 20 and swings essentially about an axis which passes transversely through shaft 40 at sheave 80 and which is generally represented by the dash line A in Fig. 2.

Fig. 5a shows a modification in the formation of the swivel arm which carries shaft carrier 41. Instead of the inner swiveling tube 82 of Fig. 5, Fig. 5a shows an inner shaft or trunnion 72a which carries tube 41 and which is held against longitudinal movement by the cross pin 13a in a manner similar to that before described. In this case however trunnion 72a is smaller than tube 71 and has peripheral grooves 72b in which rubber rings 72c are fitted and in turn fit the interior of tube 71. The rubber rings both allow swiveling rotation of trunnion 72a and carrier 41 and also provide for a certain amount of shock and vibration absorption between the traction roller and spring 28.

From what has been said of the structure and functioning of the specific preferred designs of the support of the shaft carrier, the following will be understood. The shaft carrier 41 is supported by the mounting arm 70 at a single medial point of the carrier. At that point of support the mounting means (arm 70) constrains that medial point of the carrier to movement in a generally vertical direction or plane (more specifically, in a direction toward and from both the car wheel and the accessory shaft). The swivel, which is here preferably embodied in the arm structure, then constrainedly allows independent swinging of the shaft carrier about the medial point in the same general directions or in a plane which is determined by the line of movement of the medial carrier point and by the axis of the carrier and its driving shaft.

Fig. 11 shows certain modifications in structure, among other things showing the present feature of the enclosed torsion spring applied to a mounting shaft which carries the driving shaft carrier through two arms as in the previous Van Dorn

application which has been referred to. In Fig. 11, the hollow mounting shaft 20a is shown journaled at its inner end in a fixed bracket 21a. At its outer end the mounting shaft is provided with an enlarged section 20b which is journaled over an inwardly projecting sleeve 23a whose headed outer end is mounted in the mounting plate 25a which, like mounting plate 25 of Fig. 1, may form a part of the belt housing. Head 23b of sleeve 23a is held under a cap 23c secured by cap-screws to plate 25a. Torsion spring 28a is here shown as composed of two flat leaves 28b secured at their inner ends at 29 in the same manner as described in connection with Fig. 1. As will be obvious the outer ends of these spring leaves may be adjustably anchored in the manner shown in Fig. 1; but in Fig. 11 they are shown as being bent outwardly at 28c and clamped in adjusted position under the cap 23c.

A space is provided between plate bushing 25b and the end of shaft section 20b, for accommodation of hub 91a of lifting handle 90a and of the hub 110 of an arm 111 whose swinging end is rigidly joined to the laterally outer end of shaft carrier tube 41a through a welded bracket 112. Arm 111 swings on sleeve 23a (swings about the axis of mounting shaft 20a) with some universal freedom, being provided with a soft rubber bushing 113 for that purpose. Lifting handle 90a engages lug 94a and the shaft carrier 41a in the same manner as will be explained in connection with Fig. 1.

The inner end of shaft carrier tube 41a is carried by the swinging end of an arm 114 which is rigidly mounted on mounting shaft 20a; it may be secured to that shaft by welding so that it also holds in place the block 29a. The outer end 115 fits loosely in a perforated lug 116 on shaft carrier 41a.

The described two-arm mounting allows shaft carrier 41a the same relative movements that have been described in connection with Fig. 1. The force exerted by spring 28a is applied to the shaft carrier through arm 114, at an intermediate point in the carrier length determined by the relative position of lug 116.

In the relative swiveling movement of the truck the car wheel 58 also moves relatively to the right and to the left of the normal relative position shown in Fig. 1. On movement of the car wheel to the left, the wheel tread may pass from under roller tread 57, and the traction roller may thus be pressed below the position shown in Fig. 1 to a position where its conical face 58, or even the face of extension cone 60 may be pressed down into engagement with the right-hand peripheral edge of the car wheel tread. The cone is long enough to take care of maximum movement of the car wheel toward the left, and upon return movement of the car wheel to normal position the conical surfaces will climb the tread.

On relative movement of the car wheel to the right of the position shown in Fig. 1 the conical surface of the traction roller, which normally clears the car wheel flange, will come into contact with that flange and climb it until tread 57 is riding the flange. If the car wheel continues then in its relative movement toward the right so that roller tread 57 is entirely to the left of the wheel flange, the traction roller then drops down under the pressure of the spring until the guard 65 rides the flange edge. The guard is long enough, in the direction of length of shaft carrier 41, to continue to ride the wheel flange to

the maximum movement of the wheel toward the right. The guard thus prevents the traction roller from dropping any great distance below the flange periphery; and upon return of the car wheel toward the left a short frusto-conical face 57a on tread face 57 will climb the flange. The provision of the guard 65 makes it unnecessary to have another relatively long conical surface at the right hand side of the traction roller like that at the left. The amount by which the traction roller drops after it has passed over the wheel flange is determined by the difference between the radius of roller tread 57 and the maximum radius of guard 65; and that difference need only be enough to prevent the guard from contacting the wheel tread when the roller tread 57 is normally riding the wheel tread, allowing for a reasonable amount of wear reduction of the diameter of tread 57.

The action of the traction roller has been described on the assumption that slots 74 in swivel tube 72 are sufficiently long to allow swiveling movement of shaft carrier 41 to the extents described. The slots 74 may however be so positioned and dimensioned as to limit the downward swinging of the roller end of 41 so that the extension cone 68 may not be needed as the roller will not drop below the position in which the frusto-conical surface 58 will engage the edge of the car wheel tread to climb it.

Fig. 8 shows a modification in the form and make-up of the traction roller in which a cylindric metal extension member 60a is substituted for the cone 60 of Fig. 7. Otherwise the structure shown in Fig. 8 is the same as that shown in Fig. 7 and the same numerals are applied. The cylindric diameter of 60a is substantially the same as the minimum diameter of frusto-conical tread face 58, and 60a clears the wheel flange when tread 57 is riding the wheel tread. The action of such a roller in following the car wheel is the same as that previously described except that, when the car wheel moves relatively toward the left in Fig. 1 the cylindric extension 60a continues to ride the car wheel tread after conical face 58 has left it and prevents the traction roller from dropping below a point where conical face 58 will climb the tread when the car wheel subsequently moves toward the right in Fig. 1.

Figs. 11 and 12 also show a modified traction roller structure and a modified form of guard, either of which may be used with the mechanisms of Fig. 1. The traction roller 49b as there shown is similar to that of Fig. 7, the same numerals being applied to similar or duplicate parts. The sheet metal body 54b of this roller is similar to body 54 of Fig. 7 except that its conical portion 55b is not faced by a conical rubber tread, the conical end face of the peripheral rubber tread 57b lying flush with the metallic conical face which is mainly or substantially wholly the conical face 59b of the metallic extension cone 60b. That extension cone is here affixed (e. g. by welding) at its base directly to the frusto-conical portion 55b of the main body, that frusto-conical portion being recessed as shown so as to make conical face 59b flush with the narrow annular frusto-conical surface 55c of the main roller body. This unitary roller structure is mounted on the flanged hub 51 by bolting the body flange 53 to the hub.

Figs. 11 and 12 also show a modified form of guard 65a, similar to guard 65 of Figs. 5 and 7 except that its flange contacting face 65b is tilt-

ed at a slight angle to the axis of the driving shaft and roller. The direction of tilt is such that the guard edge which lies adjacent the edge surface 57c of the roller tread is further from the shaft axis than is the opposite guard edge. That sloping guard face (see Fig. 11) is in a position where in effect it forms an outward continuation of the somewhat concaved conical tread surface 57c, and thus acts to lift the roller and to feed the conical face 57c onto the car wheel flange as the flange moves toward the roller from the right in Fig. 11.

In driving devices of the character here described for driving any car accessory, and particularly for driving an air impeller in a refrigerator car, it is desirable to provide means for disconnecting the driving connection, either so that the accessory will not be operated while the car is in motion, or so that an auxiliary drive may be applied to the accessory when the car is standing. For instance, an auxiliary driving motor may be applied directly to accessory shaft 13 through the fitting 15 by applying a belt sheave to the screw-threaded hub 15a and by then belting an auxiliary drive motor to that sheave. This, for instance, is done for pre-cooling operation of the air impeller before a refrigerator car starts its transit, or during stops to keep up the air circulation and refrigeration. In any such case it is necessary to disconnect the driving mechanism either at the traction roller or at the belt drive 81, or at both. In the particular instance here shown the effective disconnection is made at both points. For that purpose an arm 90 (see Fig. 3) has at one end a strap or hub 91 which loosely encircles the outer end of mounting shaft 20. In its normal inoperative position the arm 90 rests on a supporting lug 92 which projects inwardly from the mounting plate 25. Mounting shaft 20 has a short radially projecting arm 93 which carries a lug 94 normally located above the normal position of arm 90, as shown in full lines in Fig. 3, the clearance of the lug from the arm allowing for all normal operative rotations of mounting shaft 20. When arm 90 is raised to such a position as shown in dotted lines in Figs. 2 and 3 and hung up on an upper supporting lug 95, the arm comes into contact with lug 94 to rotate mounting shaft 20 in a direction to raise the radial swivel arm 70 and thus to raise the drive shaft carrier 41 as a whole. This general upward movement of the drive shaft carrier will tend to raise the traction roller off the car wheel and to raise sheave 80. To make certain however that sheave 80 is raised so as to relieve the normal tension on belt 81 so that the belt is not subjected to running wear when the auxiliary drive is applied, arm 90 in moving upwardly also moves up under the outer end of shaft carrier 41 to move that end of the shaft carrier, and sheave 80 with it, to such a position as is indicated in dotted lines in Fig. 3. To make certain that belt 81 moves up and lifts off the upper sheave 14 a guard may be provided to move up under the belt. Such a guard may be mounted either on handle 90 or on carrier tube 41. It is here shown, at 96, mounted on tube 41. The belt, being rather stiff and confined by the wall surfaces of chamber 11b within the car wall structure (see Fig. 2) will lift at its upper end off sheave 14.

The mounting plate 25 hereinbefore referred to may be extended to form the inner wall of a casing which encloses sheave 80 and the lower part of drive belt 81 to protect them. For purposes of easy assembly the plate has an open-

ing 100 which is large enough to pass sheave 80 and also large enough to accommodate the relative movements of the sheave end of the drive shaft. The protective casing as shown also includes bottom and side walls 101 and an outer wall 102. The casing may, however, consist entirely of these last named walls, omitting the inner wall which is here shown as formed by mounting plate 25. The casing, and the mounting plate 25, are hung, for instance by welding, from a structural member 103 which forms a part of the fabricated side sill of the car body, openings 104 and 105 being cut in that side sill structure to pass the drive belt 84. The driving belt and sheaves, being thus substantially completely enclosed within the car sill and wall structure and within the lower casing, are adequately protected.

We claim:

1. In a car structure having a body and a relatively movable running gear including a wheel and axle element; driving mechanism for an accessory which is carried by the car body and which has an actuating shaft; said driving mechanism including, a driving shaft, a shaft carrier on which the driving shaft is journalled, mounting means for the shaft carrier on the car body supporting the carrier at a single point intermediate the ends of the driving shaft, the mounting means constrainedly allowing movement of said medial point substantially along a line of movement to and from the wheel and axle element and the accessory shaft, and constrainedly allowing swinging movement of the carrier and driving shaft substantially in a plane which is determined by said line of movement and by the axis of said shaft, and two power transmitting means one between one end of the driving shaft and the wheel and axle element and the other between the other end of said shaft and the accessory shaft, both power transmitting means being rendered effective by movements of the shaft ends in said plane.

2. Driving mechanism as defined in claim 1, and in which the first mentioned power transmitting means includes a traction roller adapted to tractively engage the car wheel, and the second mentioned power transmitting means includes a sheave and belt transmission.

3. Driving mechanism as defined in claim 1, and in which the mounting means for the shaft carrier comprises a rotatably mounted mounting shaft, a radial arm mounted on the shaft, said arm including a component which is rotatable about the longitudinal axis of the arm and which carries the shaft carrier at its outer end.

4. Driving mechanism as defined in claim 1, and in which the mounting means for the shaft carrier comprises a rotatably mounted mounting shaft, a radial arm mounted on the shaft, said arm including a component which is rotatable about the longitudinal axis of the arm and which carries the shaft carrier at its outer end; and a torsion spring housed within the mounting shaft and tending to rotate it and the arm in one direction about the mounting shaft axis.

5. Driving mechanism as defined in claim 1, and in which the mounting means for the shaft carrier comprises a mounting plate carried by the car body, a rotatably adjustable plug mounted on and projecting through the plate, a hollow mounting shaft having one end journalled on the plug, a car-body supported bearing for the other end of the mounting shaft, a torsion spring housed within the mounting shaft with one end

secured to that shaft and the other to said plug, and a radial arm mounted on the mounting shaft and at its outer end supporting the driving shaft carrier, said arm embodying a swivel allowing relative rotary movement of the shaft carrier about the longitudinal axis of the arm.

6. In a driving mechanism of the character described, a driving shaft and a shaft carrier on which the driving shaft is carried, means for supporting the shaft carrier on a car body so that one end of the shaft is movable to and from a car wheel with the axis of the shaft substantially parallel to the normally positioned axis of the car wheel, a traction roller on said end of the driving shaft, a fixed guard member mounted on the shaft carrier adjacent one end of the roller and adapted to engage and ride the periphery of the car wheel when that wheel moves away from the roller in an axial direction in the movements of the car wheel relative to the car body on which the shaft carrier is mounted, the traction roller having a substantially cylindrical wheel-engaging tread, and having a conical tread extension at its end opposite the end adjacent the guard member.

7. In a driving mechanism of the character described, a driving shaft and a shaft carrier on which the driving shaft is carried, means for supporting the shaft carrier on a car body so that one end of the shaft is movable to and from a car wheel with the axis of the shaft substantially parallel to the normally positioned axis of the car wheel, a traction roller on said end of the driving shaft, and a fixed guard member mounted on the shaft carrier adjacent one end of the roller and adapted to engage and ride the periphery of the car wheel when that wheel moves away from the roller in an axial direction in the movements of the car wheel relative to the car body on which the shaft carrier is mounted, said guard having a wheel engaging face which lies at an angle to the axis of the shaft and roller, the edge of said face which lies adjacent the roller being further removed from the axis than the opposite guard edge.

8. In a driving mechanism of the character described, a driving shaft and a shaft carrier on which the driving shaft is carried, means for supporting the shaft carrier on a car body so that one end of the shaft is movable to and from a car wheel with the axis of the shaft substantially parallel to the normally positioned axis of the car wheel, a traction roller on said end of the driving shaft, and a fixed guard member mounted on the shaft carrier adjacent one end of the roller and adapted to engage and ride the periphery of the car wheel when that wheel moves away from the roller in an axial direction in the movements of the car wheel relative to the car body on which the shaft carrier is mounted, said adjacent end of the roller having a frusto-conical wheel engaging periphery, the guard having a wheel engaging face which lies at an angle to the axis of the shaft and roller, the edge of said face which lies adjacent the frusto-conical face of the roller having a radius from said axis about equal to the smaller radius of the frusto-conical face, and the opposite edge of the guard having a smaller radius from said axis.

9. In a driving mechanism of the character described, a driving shaft and a shaft carrier on which the driving shaft is carried, means for supporting the shaft carrier on a car body so that one end of the shaft is movable to and from

11

a wheel and axle element of the car with the axis of the shaft substantially parallel to the normally positioned axis of the car wheel, a traction roller on said end of the driving shaft, said supporting means embodying a hollow mounting shaft journalled on the car body and upon which the shaft carrier is mounted, a torsion spring lying within the hollow mounting shaft with one end of the spring connected to said shaft, and means for connecting the other end of the shaft to the car body with the torsion springs set in torsional tension.

10. In a driving mechanism of the character described, a driving shaft and a shaft carrier on which the driving shaft is carried, means for supporting the shaft carrier on a car body so that one end of the shaft is movable to and from a wheel and axle element of the car with the axis of the shaft substantially parallel to the normally positioned axis of the car wheel, a traction roller on said end of the driving shaft, said supporting means comprising a mounting plate carried by the car body, a settable plug mounted on and projecting through the plate, a hollow mounting shaft having one end journalled on the plug and on which mounting shaft the shaft carrier is supported, a car-body supported bearing for the other end of the mounting shaft, a torsion spring housed within the mounting shaft with one end secured to that shaft, the other end of the torsion spring engaging with the settable plug so that the spring may be set in torsion by setting of the plug.

11. In a car structure having a body and a relatively movable running gear including a wheel and axle element; driving mechanism for an accessory which is carried by the car body and which has an actuating shaft; said driving mechanism including, a mounting shaft rotatably mounted on the car body, a driving shaft, a shaft carrier on which the driving shaft is journalled, means for supporting the shaft carrier, at a point intermediate the two ends of the driving shaft, on the mounting shaft, said means comprising exclusively a single supporting arm rigidly mounted on the mounting shaft and extending radially therefrom and supporting the shaft carrier at its outer end in such manner that the shaft carrier and driving shaft swing with the arm about the axis of the mounting shaft and are allowed exclusively swinging movement with relation to the mounting shaft and the single supporting arm in a plane which is substantially parallel to the axis of the mounting shaft and which is substantially normal to the radial extent of the supporting arm, two power transmitting means one between one end of the driving shaft and the wheel and axle element and the other between the other end of the driving shaft and the accessory shaft, both power transmitting means being rendered effective by movements of the shaft ends in said plane, and a spring having one end anchored on the car body and the other end applied directly to the mounting shaft to apply rotational torque to it and thereby tending to swing the medial supported point of the driving shaft in one direction about the axis of the mounting shaft.

12. In a car structure having a body and a relatively movable running gear including a wheel and axle element; driving mechanism for an accessory which is carried by the car body and which has an actuating shaft; said driving mechanism including, a hollow mounting shaft

12

rotatably mounted on the car body, a driving shaft, a shaft carrier on which the driving shaft is journalled, means for supporting the shaft carrier, at a point intermediate the two ends of the driving shaft, on the mounting shaft, said means comprising a supporting arm rigidly mounted on the mounting shaft and extending radially therefrom and supporting the shaft carrier at its outer end in such manner that the shaft carrier and driving shaft swing with the arm about the axis of the mounting shaft and are allowed swinging movement in a plane which is substantially parallel to the axis of the mounting shaft and which is substantially normal to the radial extent of the supporting arm, two power transmitting means one between one end of the driving shaft and the wheel and axle element and the other between the other end of the driving shaft and the accessory shaft, both power transmitting means being rendered effective by movements of the shaft ends in said plane, and a torsion spring located within the hollow mounting shaft and having one end anchored on the car body and the other end applied to the mounting shaft to apply rotational torque to it and thereby tending to swing the medial supported point of the driving shaft in one direction about the axis of the mounting shaft.

13. Driving mechanism as defined in claim 12 and in which the means for supporting the shaft carrier comprises also another radially extending arm mounted to swing about the axis of the mounting shaft independently of the rotation of that shaft and supporting the driving shaft carrier near one end of the driving shaft, said arm embodying a swivel allowing relative swinging movement of the shaft carrier about the longitudinal axis of the arm.

14. In a driving mechanism of the character described, a driving shaft and a shaft carrier on which the driving shaft is carried, means for supporting the shaft carrier on a car body so that one end of the shaft is movable to and from a wheel and axle element of the car with the axis of the shaft substantially parallel to the normally positioned axis of the car wheel, a power transmitting element on said end of the driving shaft, said element being rendered effective and ineffective by said movement of the shaft with relation to the wheel and axle element, said supporting means embodying a hollow mounting shaft journalled on the car body and upon which the shaft carrier is mounted, a torsion spring lying within the hollow mounting shaft with one end of the spring connected to said shaft, and means for connecting the other end of the shaft to the car body with the torsion spring set in torsional tension.
